UNITED STATES PATENT OFFICE.

ROBERT CUNDALL, OF SHIPLEY, COUNTY OF YORK, ENGLAND.

PAPER-FOLDING MACHINE.

SPECIFICATION forming part of Letters Patent No. 429,262, dated June 3, 1890.

Application filed November 4, 1889. Serial No. 329,255. (No model.)

To all whom it may concern:

Be it known that I, ROBERT CUNDALL, a subject of the Queen of Great Britain, residing in Shipley, in the county of York, England, have invented certain new and useful 5 Improvements in Paper-Folding Machines, of which the following is a specification.

My invention has reference to machines employed for folding paper in sections—such 10 as note-paper and paper used for account-books and other purposes—the object of my invention being to fold the paper so that it will not open out of itself when laid down, and this I accomplish by giving the folded 15 paper an additional nip at the folded edge only.

In carrying out my invention I employ any ordinary form of paper-folding machine having nipping-rollers, and under such nipping-rollers or under the "striker" I employ an 20 arrangement of squeezers or an additional pair of nipping-rollers; but these rollers have a projecting knuckle or are countersunk, so as to reduce the diameter except at a given 25 point, which projects, the projecting part of one roller meeting the projecting part of the other roller as the two rollers revolve, so that as the folded paper leaves the ordinary folding-rollers or striker the said folded paper 30 drops or is conducted with its folded edge between the squeezers or additional pair of rollers, which are timed to receive the folded edges of the paper for the purpose of giving it an additional nip or squeeze, but only at 35 the folded edge, which I find so flattens the paper as to prevent the open edges from separating or opening out.

Such being the nature of my said invention, I will now make reference to the accompanying sheets of drawings, illustrative thereof, wherein—

Figure 1 is an end elevation of such parts of a paper-folding machine as is necessary to show the application of my invention; Fig. 45 2, a cross-section of same, and Fig. 3 a plan view. Fig. 4 is a side view showing a modification in the means for pressing the squeezing-rolls together. Figs. 5 to 10 each show a sectional side view of a modified form of the 50 squeezers.

A represents a portion of the frame-work of the machine; B, a pair of ordinary nipping

or folding rollers, the paper to be folded being inserted between the said nipping-rollers by means of the striker C working upon 55 the fulcrum D, arranged in the ordinary manner.

My improvements are shown by letter E, which comprise an additional pair of nipping-rollers of peculiar form, the journals of which 60 are carried by the square blocks F, supported in a slot or opening in the frame-work, such blocks F being forced together, so as to give the necessary nip to the rollers, by means of steel springs H, the effect of which will be 65 well understood by mechanicians; but the use of springs is not absolutely necessary, as the nip of the rollers can be obtained by screws or other means. The additional pair of nipping-rollers are driven by spur-gearing I, as 70 shown in plan view, Fig. 3.

It will be understood that the striker C inserts a number of sheets of paper between the first pair of nipping-rollers B, and that such sheets of paper (shown at J) will drop 75 with their folded edges between the additional nipping-rollers E, which are so timed in their rotation that the projecting parts a of the said nipping-rollers are ready to receive the folded edges just as they arrive from the upper rollers B or from the striker. Consequently 80 the said papers are nipped or squeezed, but only at the folded edges, which so flattens the paper as to prevent the open edges from separating or opening out. The striker C enters 85 the sheets of paper through the slotted table, (shown in the drawings,) and as soon as they are seized by the folding-rolls E the striker is raised. The folding-rolls advance the paper and deliver it to the squeezers, as before described, while the striker is being raised up, 90 so that a new supply of sheets to be folded may be inserted beneath it.

In Fig. 4 I have shown that the additional pair of nipping-rollers, instead of working 95 within blocks F, as already described, may work between caps or pedestals K and be drawn together by steel spiral springs L.

L' are bolts, which pass through the blocks K, and are secured to the frame A. The springs L are interposed between the long bosses on the frame and the nearest cap K, so that the two rolls have their squeezing-surfaces pressed toward each other.

Instead of employing rollers having projecting parts *a*, as shown in Figs. 1 and 2, I may employ a pair of rollers placed eccentrically, as shown at *M* in Fig. 5, which will 5 nip the folded sheets of paper in the same manner as already described with regard to Figs. 1 and 2.

Instead of employing eccentric-rollers, as shown in Fig. 5, I may employ a hinged lever 10 *G*, (see Fig. 6,) made to close intermittently against the part *H'* by eccentric *I'*, which gives the necessary nip to the said folded edges of the paper. The spiral spring *J* draws the levers away from the part *H'*.

15 Fig. 7 is a slight modification of Fig. 6, the action of the parts being the same.

Fig. 8 shows a pair of jaws *K'*, hinged at *L'*, closed at a given time by eccentrics *I'* and opened by springs; or box-cams may be 20 employed, which would both open and close the jaws.

Fig. 9 is another modification of the means of giving intermittent motion to nipping devices. In this case a crank and connecting-rod *M'* is employed to force part *N* against 25 the part *H'*.

In Fig. 10 I have shown a pair of nipping-rollers *O*, both of which are carried on separate arms *P*, working on a fulcrum *Q*. These 30 rollers are caused to nip at a given time by cams *R*; but the rollers are separated by springs *J*.

I wish to observe that the extra nip given to the folded edge of the sheets of paper, as 35 above described, is accomplished without glazing or glossing the paper, as would be the case if the nipping-surfaces of the rollers were more extended, or if the extra pair of nipping-rollers were of equal diameter throughout.

I claim as my invention—

1. In a paper-folding machine, the combination, with a pair of revoluble folding-rolls, of a reciprocating striker above the rolls for entering the paper between them, and a pair of squeezers supported below the said folding-rolls for supplementing their action and subjecting the folded edges of the sheets to additional compression, the said folding-rolls being adapted to carry forward the folded sheets of paper and to deliver them to the 50 squeezers while the said striker is being raised to permit the insertion of more sheets beneath it, substantially as set forth. 45

2. In a paper-folding machine, the combination, with a pair of revoluble folding-rolls, of a reciprocating striker above the rolls for entering the paper between them, a pair of revoluble rolls provided with longitudinally-opposed projections and journaled below the said folding-rolls for subjecting the folded 60 edges of the sheets to additional compression, and springs pressing said supplemental rolls toward each other, the said folding-rolls being adapted to carry forward the folded sheets of paper and to deliver them to the squeezers 65 while the said striker is being raised to permit the insertion of more sheets beneath it, substantially as set forth. 55

In witness whereof I have hereunto signed my name in the presence of two subscribing 70 witnesses.

ROBERT CUNDALL.
